ELECTRICAL REGULATING APPARATUS

William C. Sealey, Wauwatosa, Wis., assignor to
Allis-Chalmers Manufacturing Company, Milwaukee, Wis., a corporation of Delaware

Original application November 13, 1942, Serial No.
465,425. Divided and this application August
17, 1945, Serial No. 611,053

2 Claims. (Cl. 200—166)

This invention relates in general to electrical regulating apparatus and relates particularly to apparatus such as may be utilized in an electrical regulator in which the use of oil as an insulating and lubricating fluid is avoided. This application is a division of parent application Serial No. 465,425, filed November 13, 1942, for Electrical regulating apparatus.

In prior art step type voltage regulating apparatus, oil has generally been used both as an insulating and as a lubricating fluid. An apparatus of this type is shown in United States Letters Patent No. 2,177,109, L. H. Hill, granted October 24, 1939, which utilizes oil for lubricating the operating mechanism of the tap changer, for lubricating and insulating the tap changing switch contacts and for insulating the windings of the transformer. The problem of making electrical regulating apparatus of the above type fire proof or noninflammable therefore involves both insulating and lubricating problems.

Transformer windings have been made fire proof by the use of air as an insulating medium or by the use of synthetic noninflammable liquids. The noninflammable liquids suitable for such insulating purposes have undesirable properties requiring special equipment for handling, are hazardous from the standpoint of injury to personnel and are relatively expensive. Although air insulation necessitates greater insulating distances than does oil insulation, it is a good insulator but a poor lubricant. Prior art air insulated contacts have been lubricated, however, such lubrication has been detrimental to the current carrying capacity of the contacts.

It is therefore an object of the present invention to provide an electrical regulating apparatus with switch contacts which are air or other gas insulated but which are at the same time lubricated during relative motion thereof with a noninflammable lubricant.

It is a further object of the present invention to provide gas insulated, frictionally engaged switch contacts with a noninflammable lubricant which does not impair the current carrying characteristics of the contacts.

Objects and advantages other than those above set forth will be apparent from the following description when read in connection with the accompanying drawing in which:

Fig. 1 is a diagrammatic showing of a voltage regulating system and apparatus embodying the present invention;

Fig. 2 is a detailed view of the dial switch contacts shown in Fig. 1;

Fig. 3 is a bottom detail view of the fixed contact shown in Fig. 2; and

Fig. 4 is an end view of the contact structure shown in Fig. 2.

In Fig. 1, a tap changing switch 9 selectively connects differing amounts of a winding 8 into a load circuit 5 to control the voltage thereof. The winding 8 is excited from an exciting winding 7 connected across the supply circuit 6. The voltage of load circuit 5 is maintained constant by including more or less of the winding 8 therein in response to action of a contact making voltmeter 17.

The operating apparatus for the tap changing switch 9 includes a motor 21 connected in driving relation to a shaft 26 by a geared shaft 22 and also includes the shafts 29 and 32 driven from the shaft 22 to operate the contactors 14 and 15, respectively. The sequence of operations of the operating mechanism is such that the load circuit is made and broken at the contactors 14 and 15, thus a change in the setting of the dial switch 9 is made only when the pertinent contactor 14 or 15 is in open position. The contacts 12 and 13 of the dial switch 9 therefore do not make and break any current, but function to carry the heavy load current through selected portions of winding 8.

The operating mechanism may be insulated with a noninflammable gas and the various bearings thereof may be lubricated with oilless bearings of the type using graphite or some similar lapping compound. The contactors 14 and 15 are air break switches of any type suitable for making and breaking current in air.

The windings 7 and 8, which are on the same core, may be insulated by a noninflammable liquid or may be insulated by a noninflammable gas such as air. In the prior art structures, the dial switch 9 has been immersed in oil for insulation and for lubrication purposes. In order to make a noninflammable regulating apparatus, in the present invention the dial switch 9 is insulated by air or some similar insulating gas and is lubricated in a fire proof manner that will not impair the current carrying function of the dial switch contacts.

The dial switch 9 has fixed contact plates 10 circumferentially spaced for selective connection of one or a pair thereof into the load circuit by means of a plurality of pairs of movable contacts 12 and 13. Considerable contact pressure is desirable between cooperating fixed and movable contacts in order that the heavy load current may be safely carried thereby without over heat-

ing. The pairs of contacts 12 and 13 are each made in two parts which, as shown in Fig. 4, cooperate in rubbing engagement with opposite faces of the stationary contact plates 10. Both parts of each contact assembly are carried by guide members 43 rotatable by the shaft 36. Pins 44 are rigidly fastened to the contacts 12 and 13 and slide in cooperating holes in the guides 43. The contact pressure against the faces of contact plate 10 is provided by springs (not shown) between the guides 43 and the contacts 12 and 13.

When the contacts 12 or 13 are not contacting a plate 10, the pins 44 hold the two parts of the contact slightly apart so that they can more easily slide over the beveled edge 40 of the next plate 10. The plates 10 are mounted on supporting members 42 and are held in position by machine screws 39.

When the pairs of contacts 12 and 13 are in a tap connecting position, these contacts may be positioned as shown in Fig. 2, where both pairs of contacts cooperate with the same plate 10, or they may be on adjacent plates 10. In either case, the contacts 12 and 13 are on end, noncentral or main current carrying portions of a plate 10 when in tap connecting position, and at least one of these contacts must sweep across the central or lubricating portion of a plate 10 during selective movement in arriving at a tap connecting position.

In the prior art, a dial switch such as 9 was insulated by immersion in oil and, therefore, the problem of lubrication was simple. In the present invention lubrication between the contacts 12 and 13 and the plates 10 is provided by a lapsing compound such as graphite. The lubricant is positioned for effective action on both contact faces by inclusion in holes 38 drilled in the stationary contact 10.

As shown in Fig. 2 the graphite inserts are placed in the central or lubricating portion of the plate 10, where the graphite inserts do not interfere with the carrying of heavy currents by the dial switch contacts when in a tap connecting position. However, by placing the graphite inserts in the central portion of the contact plates 10, one or the other of the contacts 12 or 13 will sweep across the graphite and be lubricated upon movement from one tap position to the next. Use of this type of lubrication permits air insulation to be used for the dial switch 9.

If the voltage of the circuit 5 varies from normal the contact making voltmeter 17 responds to the increased or decreased pull of the coil 18 to close contact 19 or contact 20. The motor 21 is thereby energized in a proper direction and turns the shaft 22. A gear 23 on shaft 22 is provided with three pins 25, 26 and 27 which coact with the gears 30 and 33 to operate the switches 14 and 15.

In the position shown in Fig. 1 the gear 23 has been rotated in the counterclockwise direction and the pin 25 has turned the gear 30 one-third of a revolution thereby opening the switch 14. This movement of the switch 14 was effected by turning of the shaft 29 and eccentric 28. During this movement, a second gear 34 on the shaft 22 was rotated in a counterclockwise direction to the position shown where one of the pins 35 is meshed with the gear 31. Further counterclockwise rotation of the shaft 22 will move the dial

switch in a clockwise direction so that brush 12 occupies the present position of brush 13 and brush 13 is moved to the next contact plate 10.

During this rotation of the shaft 22, the pin 26 and the gear 23 will have moved the shaft 29 a third of a revolution thus placing the switch 14 in a position to be closed upon further rotation of the shaft 22. The closing of switch 14 is accomplished by the pin 27 giving the shaft 29 a final one-third movement, closing the switch 14 after the contact 13 has reached the end portion or noncentral portion of the next contact plate 10. If a further voltage change in the same direction is initiated by the contact making voltmeter 17, a further clockwise rotation of the dial switch is obtained with the switch 15 breaking the circuit to the brush 12 and making it after the brush 12 has reached the new contact position. This is accomplished by action of the pins 25, 26 and 27 on the gear 33 to actuate the switch by means of the shaft 32 and the eccentric 31. One-half of the auto-transformer 16 takes the load current when the switch 14 or 15 is open.

The motor is shown as being energized from the load circuit 5, however, it may be energized from a winding on the same core as the windings 7 and 8. The switches 1 and 15 are connected in circuit, respectively, with the brushes 12 and 13 through the collector rings 11, the brush 12 being insulated from the ring contacting the brush 13 by an insulating member 45.

Although but one embodiment of the present invention has been illustrated and described it will be apparent to those skilled in the art that various changes and modifications may be made therein without departing from the spirit of the invention or from the scope of the appended claims.

It is claimed and desired to secure by Letters 40 Patent:

1. In a plural circuit switch, a fixed contact provided with contact faces on opposite sides thereof, said contact provided with a plurality of main current carrying portions, a lubricating portion positioned between said main current carrying portions, inserts of solid lubricating material in said lubricating portion only and extending through said contact from one of said contact faces to the other of said contact faces, and a plurality of pairs of movable contacts arranged to cooperate in rubbing engagement with opposite faces of said main current carrying portions to normally close a heavy current load circuit and arranged to cooperate in rubbing engagement with opposite faces of said lubricating portion only during movement of said movable contacts.

2. A switch comprising a fixed contact provided with a plurality of main current carrying portions, a lubricating portion positioned between said main current carrying portions, a movable contact, means for moving said movable contact in rubbing engagement with said lubricating portion only during movement of said movable contact from one to another of said main current carrying portions, and inserts of solid lubricating material in said lubricating portion and extending to the surface thereof engaged by said movable contact.
